UNITED STATES PATENT OFFICE

2,660,850

SPINDLE MOISTENER

John D. Rust, Pine Bluff, Ark.

Application April 25, 1950, Serial No. 158,039

4 Claims. (Cl. 56—41)

1

The special object of this invention is to provide a simple, inexpensive and effective device for moistening cotton picker spindles. My new moistener consists primarily of a vertical series of rubber flipper elements. The metal frame which carries the flipper elements is located in a stationary position and the flippers are held at such an angle that they are substantially parallel with the spindles. A live resilient rubber of suitable thickness is used for the flippers and the rapid passing of the spindles between the flippers causes a rapid vibration or flipping of the edges of the rubbers so that any surplus liquid is generated into a fine mist. This results in an even distribution of the liquid to all the spindles.

I have found that by adding a second series of flippers, spaced from the first series a distance sufficient to enable the spindles to clear the first series before engaging the second series, the process is improved. Therefore in practice I am using two vertical series of flippers positioned in tandem.

With my present device it is possible and desirable to feed the liquid directly onto the spindles prior to their engagement with the flippers. The liquid is fed by gravity through suitably located nozzles directly onto the spindles. However, I do not wish to be limited to this particular method of feeding the liquid onto the spindles. Various means of applying moisture to the spindles could be used before or at the time of contact with the flippers. The flippers would still generate a mist which would moisten the spindles effectively. I have shown what appears to be the simplest application of the invention.

To the attainment of the aforesaid objects and ends invention still further resides in the novel details of construction, combination, and arrangement of parts, all of which will be first fully described in the following detailed description, and will then be particularly pointed out in the appended claims, reference being had to the accompanying drawing, in which:

Fig. 1 is a top plan view with parts broken away of so much of a cotton picking unit as is necessary to illustrate the application of the present invention.

Fig. 2 is an elevation, looking in the direction of the arrow *a* in Fig. 1, on an enlarged scale.

Fig. 3 is a detailed view on an enlarged scale, showing a liquid dispensing unit in relation to a spindle carrying slat, the view being taken in the direction of the arrow *b* in Fig. 1.

2

Fig. 4 is an enlarged detail sectional view on the line 4—4 of Fig. 3.

In the drawing, in which like numerals of reference indicate like parts in all the figures, 1 and 1^a indicate the longitudinal beams, and 2, 3, and 4 the cross beams of the picker unit frame. 5 designates the drive shaft having sprockets 5^a around which the endless conveyor chains 10 pass. The chains 10 also pass between guides 6, 7, 8, and 9.

11 designates the spindles of the vertically disposed spindle carrying slats 12, the spindles having driving rollers 13.

All of the foregoing enumerated parts are shown in my prior Patent 2,085,046, of June 29, 1937, and are well known and, per se, constitute no part of the present invention.

The longitudinal beam 1^a has detachably secured thereto by suitable brackets or arms, not shown, supporting plates 14 to which are secured one or more vertically extending angle irons 15. The angle irons 15 may be affixed to the supporting plates 14 by welding or any other suitable means, not shown. The angle irons 15 have mounted thereon, preferably by welding, a plurality of vertically spaced arms or plates 16 to which are clamped flat resilient flipping wiper members 17 preferably formed of rubber, which approximately abut one another, as shown in Fig. 2. The rubber flippers also serve as spindle wipers and are held on the arm plates 16 by means of clamp plates 18 and screws 19.

20 designates a liquid supply pipe which is connected by any suitable means, not shown, to the guide 8 and supported thereby and from which a number of branches 21, 22, 23 extend downwardly and inwardly between rows of spindles to deposit liquid on the same. Each of the branches or nozzle pipes 21, 22, 23 has a separately controlled valve, 24, 25, 26 respectively, through the adjustment of which the required amount of liquid is deposited on the spindles. By depositing the liquid through the medium of a plurality of nozzle pipes instead of through a single pipe over the top of the spindle paths a more equal distribution of the liquid on the spindles is obtained.

By reference to Fig. 1 it will be seen that the flipper units (composed of the parts 16, 17, 18, 19) extend inwardly from the angle irons 15 toward the endless chain conveyor 10 and are disposed in the path of the spindles 11 and substantially in the vertical plane of the spindles in order that the entire picking portion of the spindle will pass between adjacent flippers. In this

way there is only one spindle at a time passing between adjacent flippers 17, with the result that as soon as a spindle passes between adjacent resilient flippers the free edge of the flippers will flex or snap back, which action causes the greater portion of the liquid which has been wiped from the spindles by the free edge portions of the flippers to be thrown therefrom into the surrounding area. This flexing of the flippers and the throwing therefrom of the liquid wiped from the spindles produces a mist through which the spindles pass. When two flipper devices are used, as shown in Fig. 1, they should be spaced sufficiently apart so that not more than one spindle of a row passes through the flipper device at a time.

I am aware that heretofore structures similar to that shown in Figs. 1 and 2 have been used to wipe spindles, but all such structures of which I have knowledge have been angled in a direction opposite to that shown in Fig. 1, i. e., at an approximate right-angle to the spindles so that always more than one spindle is passing through between wiper elements at a time, with the result that the wipers are not caused to snap back and forth as an agitator to produce any mist through which the spindles pass; and consequently such other devices can not effect the results produced by my present arrangement.

From the foregoing description, taken in connection with the accompanying drawing, it is thought that the construction, operation and advantages of the invention will be clear to those skilled in the art.

What I claim is:

1. A spindle moistener for a cotton picking unit comprising a frame having an endless spindle carrying conveyor, means on said frame for delivering liquid to the spindles on said conveyor, a plurality of resilient wiper members detachably mounted on said frame and positioned in the path of said spindles and disposed substantially in the vertical plane of said spindles when said members and spindles are in engagement, said wiper members engaging said spindles prior to the spindles engaging the cotton, said wiper members upon being flexed by said spindles flipping the excess liquid therefrom in the form of a mist through which said spindles pass.

2. A spindle moistener for a cotton picking unit comprising a frame having an endless conveyor with a plurality of vertically disposed spindle carrying slats, a nozzle on said frame for delivering liquid to the spindles on said slats, wiping elements positioned in the path of the spindles and adapted to engage said spindles prior to the spindles engaging the cotton, said wiping elements including a support detachably mounted on said frame, a plurality of arms secured to said support, resilient members affixed to said arms and arranged in approximately abutting relation with one another, said resilient members being disposed substantially in the vertical plane of

said spindles when said members and spindles are in engagement, said resilient members engaging the spindles of one slat, upon the movement of said conveyor, for wiping excess liquid from the spindles and flipping from the edge portion of said resilient members the excess liquid to produce a mist prior to said resilient members engaging the spindles on the next succeeding slat.

3. A spindle moistener for a cotton picking unit comprising a frame having an endless conveyor with a plurality of vertically disposed spindle carrying slats, a liquid supply pipe mounted on said frame, a plurality of spaced nozzles connected to said pipe and positioned in the path of the spindles, wiping elements positioned in the path of the spindles and adapted to engage said spindles prior to the spindles engaging the cotton, said wiping elements including a support detachably mounted on said frame, a plurality of arms secured to said support, resilient members affixed to said arms and arranged in approximately abutting relation with one another, said resilient members being disposed substantially in the vertical plane of said spindles when said members and spindles are in engagement, said resilient members being flexed upon engaging the spindles of one slat, upon the movement of said conveyor, for wiping excess liquid from the spindles to produce a mist prior to engaging the spindles on the next succeeding slat.

4. In a cotton picking unit comprising a frame having an endless conveyor with a plurality of vertically disposed spindle carrying slats, a moistener for the spindles including a nozzle mounted on said frame and disposed in the path of the spindle for delivering liquid to said spindles, means positioned in the path of the spindles for engaging and wiping excess liquid from the spindles on one slat before engaging the spindles on the next succeeding slat for producing a mist through which said spindles pass, said means including a support detachably mounted on said frame and having a series of vertically spaced arms through which the spindles pass upon movement of the conveyor, a plurality of resilient flipping wiper members secured to said arms and disposed in approximately edge to edge relation for engaging said spindles, said flipping wiper members being positioned in a plane approximately parallel to the axes of the spindles when said spindles move between said arms.
